UNITED STATES PATENT OFFICE.

TOBIAS M. FEDER, OF BROOKLYN, NEW YORK.

ELECTRIC HEATER.

1,426,166.

Specification of Letters Patent. Patented Aug. 15, 1922.

Application filed December 7, 1921. Serial No. 520,529.

To all whom it may concern:

Be it known that I, TOBIAS M. FEDER, a citizen of the United States, residing at Brooklyn, in the county of Kings and State 5 of New York, have invented certain new and useful Improvements in Electric Heaters, of which the following is a specification.

This invention relates to electrically generated heaters, and has particular reference 10 to that type which can be screwed into a common type of socket used for lighting fixtures in the average building, and the main object is to provide a heater which can be adjusted to any angle in any universal 15 plane and thereby project the heat rays downwardly or in any other desired direction.

Another object is to provide a reflector 20 which will reflect the heat rays downwardly thus diffusing the heated air over a greater area than would be possible if directed upwardly from its source.

Still another object is to provide a heating device having extreme interchangeability of parts, effective and simple in operation and comparatively inexpensive in cost of manufacture.

These and other objects will become apparent in the description below in which 30 characters of reference refer to the like-named parts in the drawings.

Referring briefly to the drawing—

Figure 1 is a transversely sectioned elevational view of the device showing the constituent members in place.

Figure 2 is a longitudinal elevation of the device having the reflector and heating element removed.

Figure 3 is a bottom plan view looking 40 into the reflector end.

Figure 4 is an enlarged fragmentary section of the ball joint and illustrates the novel means of securing the suspended portion in any desired angular position.

Figure 5 is a side elevation of the heat-coil hanging stud.

Referring more in detail to the drawing, the numeral 10 indicates a tubular shell having a shoulder surmounted by the collar 50 11 formed at its upper end. A hollow sleeve 12 preferably of some insulating material is riveted to the exterior surface of collar 11 and extends upwardly therefrom. A flanged cover 14 is secured to the upper end of shell 55 12 and has a centrally formed contact lug 15 thereon.

Member 13 is fitted over sleeve 12 and has rounded-threads 16 thereon, by which the entire device can be secured in the socket fixture of an electrical circuit. 60

The lower end of shell 10 is formed into a pair of spaced parallel ears 17 having threaded holes therein and in which are secured the screws 18.

Screws 18 thread into the opposite sides 65 of ball 19 and retain the same between the ears 17. Similar screws 18' are threadably secured to the ball 19 at right angles to screws 18 and engage ears 21 thereby forming suspension pivots for the lower shell 70 22. It is apparent from Figures 1 and 2 that the shell 22 can be rotated in two planes about the center formed by ball 19 thus permitting a universal radial adjustment 75 of the suspended shell 22 with respect to the upper shell 10.

The lower end of shell 22 forms a sleeve 23 to which is attached a parabolic-shaped reflector 24 having its internal surface 26 burnished so as to reduce heat radiation 80 through the reflector to a minimum.

Brackets 25 riveted to the inner surface of sleeve 23 extend downwardly and have a metallic spheroidal sector 27 secured thereto.

A plurality of opened eyes 30 having 85 threaded stems 29 by which they are attached to the underside of member 27, are adapted to receive a heating coil 32 arranged in the form of a spiral. When assembling the eyes 30 are open and have a heat insulating strip 31, preferably of mica, cemented in place between the ears. When attached to their proper place on member 27 the heat-coil 32 is next inserted between the ears 90 after which the latter are bent around the 95 coil so as to form a split retaining eye and consequently readily accommodating itself to the inherent expansion and contraction due to the extreme temperature change when putting into or taking out of use. 100

Member 27 is preferably made of a heat-resisting material. As the coil 32 is in a state of continual incandescence during use, an additional mica plate 28 is retained between the coil and member 27 so as to prevent oxidation and further insulate both members from each other. 105

In order to retain the shell 22 in the various angular positions screws 18 and 18' are provided with square projections 35 upon 110 which are slidably secured radially corrugated washers 37. Similarly corrugated

washers 38 are secured in the hole 39 by means of a forced bit. From Figure 4 it is apparent that by moving the ball 19 angularly, the washer 38 will be rotated coming 5 to rest again in one of the other corrugated recesses of fixed washer 37. As the latter is urged into contact with washer 38 by the spring 36, it will be seen that the movable lower shell will be releasably held in any 10 desired position until further adjustment is made.

In use the upper end is threaded into a socket fixture through member 13 and 14 which have wires 33 and 34 respectively, secured thereto. The said wires extend downwardly through upper shell 10 and enter the lower shell 22 through the hole 20 in ball 19, after which they are joined to the inner and outer ends of the spiral coil 32 thus 20 completing the circuit.

It is to be understood that certain changes in form and structure, such as arranging the heating coils into different groupings, may be made, without departing from the spirit 25 and scope of the invention.

A wire guard 40 secured over the open end of reflector 26 is provided so as to prevent a person from tampering with the coil or otherwise endangering the same.

30 I claim:

1. An electric heating device comprising an upper and lower shell member, a parabolic reflector secured to the lower member, means for energizing a heating coil and 35 means for securing the device in a socket.

2. An electric heating device comprising upper and lower shell members, a threaded sleeve secured to the upper shell member a cover member above the shell member, an 40 insulating sleeve adapted to separate the threaded sleeve from the cover secured to the upper shell member and means for energizing a heating coil.

3. An electric heating device comprising upper and lower shell members, a ball pivotally suspended between ears of the upper shell member, said lower member having similar ears pivotally attached to the said ball at right angles to the upper shell member, a parabolic reflector secured to the lower 50 shell member and adapted to reflect heat rays downwardly, means for releasably retaining the lower shell in angular position and means for securing the device in a socket. 55

4. An electric heating device comprising an upper shell member having a threaded contact sleeve and a contact cover secured thereto, a lower shell, a ball pivotally connecting the shell members to each other, a 60 spheroidal sector secured to lower shell, open-ended eye studs threadably secured to the underside of the spheroidal sector, a heating coil secured within the eye studs, wires extending downwardly through the 65 several shell members connecting the contact plates with the heating coil and means for releasably retaining the lower shell in any angular position.

5. An electrical heating device comprising 70 upper and lower shell members having ears formed to their adjacent ends, a ball member forming a universal joint between the said shells, screws threadably engaging the ears of the shell members and the ball, a 75 square stud extending from said screws, radially corrugated washers secured in holes in the ball member, similarly corrugated washers slidably mounted on the square studs, and adapted to releasably engage the 80 aforesaid washer, springs retained on the said studs and adapted normally to urge the washers into mutual contact with each other, and means for energizing a heating coil.

In witness whereof I affix my signature. 85
TOBIAS M. FEDER.
